VEHICLE HEAD-LAMP.

1,366,946.

Specification of Letters Patent.

Patented Feb. 1, 1921.

Application filed August 26, 1916. Serial No. 116,998.

To all whom it may concern:

Be it known that I, THOMAS W. ROLPH, a citizen of the United States, residing at Cleveland, county of Cuyahoga, State of 5 Ohio, have invented certain new and useful Improvements in Vehicle Head-Lamps, of which the following is a specification.

My invention relates to projector lamps and more especially to lamps for use on vehicles.

The object of my invention is a lamp which distributes the light to the roadway in a more efficient and satisfactory manner than has hitherto been possible. More particularly, the object is to eliminate all glare and at the same time make use of all light rays issuing from the source for illuminating the points in the roadway which need the illumination most.

An important feature of my invention resides in a novel redirecting means for modifying the direction of the light rays after reflection, and in accordance therewith the degree of refraction depends upon the dis-

tance of the corresponding reflecting element from the light source. This avoids certain difficulties usually encountered with light sources of distributed form, as the electric incandescent filament lamp, which 30 cannot be combined with reflectors in common use to obtain uniform directional projection from all elements of the reflector.

For instance, with a given light source located substantially at the focal point of a 35 parabolic reflector, the reflected light from each reflecting point is spread through a certain angle which depends upon the angle subtended by the lamp filament from that point on the reflector. This subtended

angle in turn depends upon the distance of the reflecting element or point from the light source, the more remote the reflector the smaller the angle subtended, and vice versa. In accordance with this principle,

I design my correcting prisms with a progressively increasing refractive power as the corresponding reflecting elements approach the light source, and in the particular application to non-glare headlamps

50 the headlight plate has the correcting prisms horizontally arranged and progressively decreasing in angle or refractive power from the center outward.

In accordance with another feature of 55 my invention I incorporate into the head-

light plate a series of directing prisms for giving to the light the proper spread, and preferably these prisms are so designed and combined with the horizontally disposed prisms above set forth in such a manner 60 that the roadsides are illuminated in an efficient and scientific manner from a point near the vehicle to the limit of the projection. To this end these spreading prisms are vertically arranged and designed to 65 have gradually decreasing refractory power from the center of the plate in radial directions, the variation in the refractive angle preferably corresponding to the progressive change in the refractory power of 70 the above noted horizontally disposed prisms. With this arrangement the roadway surface is continuously illuminated from a point near the vehicle to the limit of light projection, and the roadsides are 75 illuminated to practically the same depth at all points of the roadway, while the reflection of the rays above the horizontal plane is entirely avoided.

Inasmuch as the parabolic reflector is 80 pretty generally used in vehicle headlamps, I have illustrated my invention as applied to this type of reflector, and my invention particularly contemplates a headlight plate embodying the above features and adapted 85 to be used with the parabolic reflectors generally used in practice.

For a better understanding of my improved projector and headlight plate, reference may be had to the accompanying 90 drawings, Figure 1 of which is a diagrammatic illustration of the principle on which my invention is based; Fig. 2 is a front view of a headlight plate; Fig. 3 is a sectional view of the headlight plate on the line 3-3 95 of Fig. 2; Fig. 4 is a front view of a headlight plate embodying another feature of my invention, and Fig. 5 is a sectional view of the headlight plate taken on the line 5-5 of Fig. 4; Fig. 6 is a vertical sectional view 100 illustrating a headlight plate having on one face the prisms shown in Figs. 2 and 3, and on the other face, the prisms shown in Figs. 4 and 5.

Referring to Figs. 1, 2 and 3, a parabolic 105 reflector 1 and an incandescent lamp 2 of a common type used in projectors for vehicles are illustrated. The lamp 2 has a filament 3 which is located substantially at the focal point of the reflector 1. As is well 110

known, the light emanating from the focal point, as indicated by the dotted lines, issues from the reflector in lines parallel with the axis, but light also issues from every point 5 in the light source and all of the rays which do not issue from the focal point will issue from the reflector at angles inclined to the parallel rays. The rays of maximum inclination are those issuing from the extreme 10 limits of the light source 3, as indicated by full lines, these lines being drawn to certain points of the reflecting surface of the reflector. As indicated, at each point on the reflector the reflected light is spread through 15 a certain angle which depends upon the angle subtended by the lamp filament from that point on the reflector, and this angle in turn depends upon the distance of that point on the reflector from the light source. It is 20 apparent, therefore, that from a point at the back of the reflector which is relatively near the light source the angle of reflected light is considerably larger than from a point near the edge of the reflector which is 25 farther or more remote from the light source. For example, with a lamp filament of certain dimensions located at the focus of an 8" parabola, the reflected light is spread 42° each side of the horizontal at 30 the point of approximate maximum spread or inclination, while at the outer edge of the reflector where the spread is close to the minimum the angle of spread is only 1½° each side of the horizontal, the optical axis 35 of the projector being horizontally disposed.

It is important to avoid these rays above the horizontal, which, as known, cause glare to approaching drivers, and I avoid them by incorporating in the headlight plate 4 a 40 series of horizontally disposed refracting prisms 5 which receive the reflected rays and bend them to or below the horizontal, but in designing and arranging these refracting elements I take into account the variation 45 of the spread of the rays on the different points on the reflecting surface and make the prisms of different refractive powers or angles so that a prism has an angle which corresponds to the spread of the rays on the 50 corresponding reflecting element. The angle here referred to is that between the faces of the prisms 5 and the vertical, the refractive power of the prisms being readily determined by this angle, as is generally 55 known. Specifically, I lay off the surface of the plate into a number of zones, in the particular modification shown, four zones A to D, inclusive, and I make the prisms located in one zone of the same angle or refracting power; but these differ in angle from that of the prisms located in the other zones. For instance, the prisms 5 in zone A, which are located in the center of the plate, have a refracting power sufficient to 60 bend the rays not less than 4½° in the specific 65

instance shown, so that none of the rays is permitted to pass through this zone above the horizontal. In zone B, however, the prisms may be of a smaller angle inasmuch as the prisms in this zone correspond to elements on the reflecting surface which have a smaller spread than that in zone A, and in the specific instance shown the prisms in zone B have a refractory power or angle sufficient to bend the rays not less than 3½° below their normal direction. In like manner, zones C and D have prisms of still smaller angles, the rays in each case being bent into parallelism with the horizontal or below the horizontal. It is apparent, therefore, that these horizontal prisms are divided into longitudinal sections, the sections corresponding to the various zones through which they happen to pass and the refracting angle of the sections decreasing in both 85 directions with reference to a vertical line 3—3 through the plate. With this arrangement it is to be noted that the surface of the roadway is continuously illuminated from a point near the vehicle to the limit 90 of the projection. The prisms in zone A light the surface of the roadway at a point near the vehicle, while the prisms in zone B illuminate the surface at a still farther distant point; and in like manner zones C 95 and D illuminate the surface at still farther distant points, a practically uniform illumination being obtained for the surface of the roadway from the nearest to the remotest points.

Theoretically, the redirecting prisms should gradually change in angle from the center of the plate to the outer edge. In order to simplify the design and manufacture, however, it may be sufficiently accurate 105 to divide the plate into zones as indicated.

Figs. 4 and 5 show a series of spreading prisms which may be used separate from and independent of the horizontal redirecting prisms, but are of special utility when combined therewith for distributing the light in the most satisfactory manner for road illumination. In order to illuminate the roadway to the best advantage, it is desirable to spread the light to a greater angular 110 distance to the side at a point near the automobile than at a considerable distance ahead thereof. For example a lateral spread of 15° might illuminate the roadway out to 20 feet on each side of the car at a point not far 120 in front of the car. At a point a considerable distance, however, the same degree of lateral spread would illuminate the roadway 40 or 50 feet on each side. This wide spread at a great distance in front of the 125 car is undesirable as being unnecessary and results in a waste of light which could be better used in obtaining a higher intensity of illumination with a very slight lateral spread. Consequently, it is desirable to 130

spread laterally the light passing through the plate in zone A a greater degree than the light passing through the plate in zone B, and to spread the light in zone C less than in 5 zone B, etc. The same idea of concentric division of prisms may, therefore, be applied to the spreading prisms on the plate, as above described in connection with the horizontal prisms. In accordance with this 10 principle, the prisms 6 in zone A are designed to give wide spread of light, while the prisms in zone B give a medium spread of light; the prisms in zone C a slight spread, and the prisms in zone D preferably 15 have no spread of light at all, although it may be desirable to have the prisms in this outer zone give a slight spread. It is apparent, therefore, that the spreading prisms are divided into zones by concentric circles 20 making the prisms in a zone of the same spreading angle and making the degree of spread of the prisms decrease in passing from the central zone to a zone at a greater distance from the center. 25 In the specific embodiment shown, the vertical prisms are illustrated as being on the outside of the plate, and the horizontal prisms on the inside thereof, but it is obvious that either of the groups of prisms may be 30 located on the inside or on the exterior, according to choice. Preferably the two groups are on the opposite sides of the plate as is shown in Fig. 6, and it is obvious also that either group may cover only a part of 35 the surface of the plate instead of the entire surface.

What I claim and desire to secure by Letters Patent of the United States, is:

1. In a projector, the combination of a 40 light source, a reflector mounted in back thereof and a plate mounted in front of said light source provided with a series of transversely extending prisms receiving rays from the source after reflection by the reflector, the angles of the said prisms decreasing gradually in successive zones from the center of said plate to the periphery thereof substantially in all directions thus forming 45 successive zones gradually decreasing in refractive power from the center of the plate. 50

2. In a projector, the combination of a light source and a reflector mounted in back of the same with a plate having a series of transversely extending refracting prisms 55 disposed on both sides of a horizontal plane passing through said light source and symmetrically disposed with reference to a point in said plane directly in front of the center of said light source, the refractive angle and 60 the refractive power of said prisms decreasing progressively as the distance from the said point increases in substantially all directions in the plane of said prisms.

3. In a projector, the combination of a 65 light source and a parabolic reflector mount-

ed in back of said light source of a circular headlight plate mounted in front of said light source and having thereon a series of transversely extending refracting prisms, the refractive angle and the refractive power 70 of said prisms increasing progressively from the center along any radius to the circumference of said headlight plate.

4. In a projector, the combination of a light source and a parabolic reflector mounted 75 in back of the same with a substantially circular headlight plate mounted in front thereof having a series of horizontal prisms thereon, said prisms being divided into sections of different refractive powers and angles and said refractive powers and angles decreasing from the center along any radius to the circumference of said headlight plate.

5. In a projector, the combination of a 80 parabolic reflector and an electric incandescent filament lamp located substantially at the focal point, with a headlight plate comprising a series of horizontal refracting prisms, said prisms being divided by concentric circles into zones of prisms of different 85 refractive angles progressively decreasing from the center outward.

6. In a projector, the combination of a 90 parabolic reflector and an electric incandescent filament lamp located substantially at the focal point, with a headlight plate embodying a series of horizontal refracting ribs progressively decreasing in angle from the center of the plate in radial directions, and other ribs vertically disposed for 95 spreading the light after reflection and also having angles progressively decreasing from the center of the plate in radial directions.

7. In a projector, the combination of a 100 parabolic reflector and an electric incandescent filament lamp located substantially at the focal point, with a headlight plate embodying in one surface a series of refracting ribs horizontally disposed for bending the light downwardly, and on the other surface 105 a series of vertically disposed spreading ribs, said ribs being divided by concentric circles into zones of progressively decreasing refractive powers from the center outward in radial directions. 110

8. A headlight plate embodying a series of refracting ribs, said ribs being divided by concentric circles into zones of progressively decreasing refractive powers from the center outward in radial directions and 120 above and below said center.

9. A headlight plate embodying a series of substantially vertical spreading prisms divided by concentric circles into zones of progressively decreasing refractive powers 125 from the center of the plate outward in radial directions and above and below said center.

10. A headlight plate embodying on one surface a series of refracting ribs divided by 130

concentric circles into zones of progressively decreasing refractive powers from the center of the plate outward in radial directions, and on the other surface a series of spreading ribs.

11. A headlight plate embodying on one surface a series of refracting ribs and on the other surface a series of spreading ribs at right angles to the aforesaid prisms, said plate being divided by concentric circles into zones of ribs of progressively decreasing angles from the center of the plate outward in radial directions.

12. A headlight plate provided with a series of substantially horizontally extending refracting ribs and a series of substantially vertically extending light spreading ribs, said horizontally extending ribs being divided into concentric zones and the ribs of the zones farther from the center being of less refractive power than those closer to the center.

13. A headlight plate provided with a series of substantially vertical ribs arranged on both sides of the center of said plate said ribs being of decreasing refractive angle or power as the periphery of said plate is approached.

14. A cover glass having thereon a series of horizontal prisms, the vertical refractive power of each prism being less at its ends than at its center.

15. A cover glass having thereon a series of horizontal prisms of varying refractive power, the vertical refractive power of each prism being less at its ends than at its center.

16. A headlight cover, the vertical refractive power of which is greater at several

points in its medial vertical plane than at points away from such medial plane but in 40 the same horizontal planes.

17. A headlight cover in which the vertical refractive power varies at points in the same horizontal plane, decreasing from the center outwardly.

45 18. In a lighting system, the combination with a light source, of a mirror reflecting the rays thereof, and a refracting cover glass, the vertical refractive power of such glass being greater adjacent to the center of a 50 horizontal plane therethrough than at points in such plane farther away from the center.

19. The combination with a reflector and a light source located at approximately the focal point thereof, of a cover plate for the 55 reflector having refracting elements thereon so located as to receive light from the source after reflection by the reflector, the refractive power of the elements on both sides of the center along at least one diameter of the 60 plate generally varying inversely from a maximum at the center inversely with their distance from the center.

20. A refracting cover plate for a reflecting projector, the refraction produced by a 65 plurality of parts thereof located on both sides of the center along at least one diameter of the plate being in the same general direction, and varying in extent from a maximum at the center inversely with the 70 distance of each of such parts from the center.

In witness whereof, I have hereunto set my hand this 24th day of August, 1916.

THOMAS W. ROLPH.
